UNITED STATES PATENT OFFICE

VALENTIN HERWIG, OF BERLIN-WILMERSDORF, AND ERNST MUSTIN, OF MAHLOW, NEAR BERLIN, GERMANY, ASSIGNEES TO FRIED. KRUPP AKTIENGESELLSCHAFT, OF ESSEN-ON-THE-RUHR, GERMANY

RAILWAY TIE

Application filed October 30, 1931; Serial No. 572,398, and in Germany October 30, 1929.

The invention relates to railway cross-ties and more particularly to ties of the class which have upper transverse ribs intended to hold the foot of the rail in position in a lateral direction. The invention primarily consists in the fact that the transverse ribs extend the entire width of the top surface of the tie without any interruption and are integral with the tie, and that each of these ribs includes a cavity or chamber for the fastening means, which chamber is closed toward the foot of the rail.

In order that the invention may be clearly understood and readily carried into effect, three embodiments of the same are illustrated by way of example in the accompanying drawings in which

Figure 1 is a cross-section of the improved tie forming the first embodiment,

Figure 2 is a fragmentary top view thereof, Figure 3 is a section on line III-III of Figure 2,

Figure 4 is a cross-section similar to that of Figure 1 and shows the second embodiment of the invention,

Figure 5 is the corresponding top view, Figure 6 is a section on line VI-VI of Figure 5,

Figure 7 is a cross-section through a tie forming the third embodiment,

Figure 8 is a corresponding top view, and Figure 9 is a section on line IX-IX of Figure 8.

The embodiment illustrated in Figures 1 to 3 will be described first.

Referring to these figures, 1 denotes the tie which is provided with two ribs 2 at the foot of the rail designed to be supported by the tie and are arranged at a mutual distance, which is but little greater than the width of the rail foot. These ribs 2 extend the entire width of the top 3 of the tie. They are formed by providing reenforcing ribs 7 on the underside of the tie top, as indicated in dotted lines in Figures 1 and 3. These ribs 7 then are pressed toward the top wall of the tie so that instead of these lower ribs 7 upper transverse ribs 2 are produced.

These reenforcing ribs 7 are provided on the tie in the course of rolling the latter.

The walls of the ribs 2 facing the rail foot extend uninterruptedly across the entire width of the tie surface, as clearly shown in Figures 1 and 2.

Furthermore, according to the invention, each rib 2 includes a chamber 4 intended to lodge the head of the respective fixing bolt.

This chamber is open toward the underside of the top wall of the tie and on that side of the rib which is remote from the rail foot,

while at the top it has a slot 5 which receives the shank of the fixing bolt. Below this slot 5, the chamber 4 has two supporting faces 6 for the T-shaped head of the bolt. The

chambers 4 may be produced by a punching operation which may be combined with the pressing operation employed to press the

above-described reenforcing ribs 7 toward the top wall of the tie to form the ribs 2.

In order to obtain a secure seat on the tie for the rail foot the part 8 of the top surface of the tie situated between the two companion ribs 2 may be given a convex shape, as

indicated in Figure 1. The tie hereinbefore described assures a very reliable guide, seat and fixation of the rail and, in addition, manufacture is simple and economical.

In the second embodiment illustrated in Figures 4 to 6, the tie 9 has transverse ribs 11, extending the entire width of the top wall of the tie.

These ribs 11 are hollow and open on the underside. They are produced by pressing them out of the top material 10.

The wall 12, facing the foot of the rail, places where the rail is to rest. These ribs 11 are signed to be fixed upon the tie, likewise has extend in parallel with the outer edges of the tie, the rail foot has a cavity or recess 13 adapted to lodge the T-shaped head of the respective width of the rail foot. These ribs 11 extend the entire width of the top 3 of the tie. They are formed by providing reenforcing ribs 7 on the underside of the tie top, as indicated in dotted lines in Figures 1 and 3. These ribs 7 then are pressed toward the top wall of the tie so that instead of these lower ribs 7 upper transverse ribs 2 are produced.

However the wall of each rib 11, remote from the rail foot has a cavity or recess 13 adapted to lodge the T-shaped head of the respective width of the rail foot. These ribs 11 extend the entire width of the top 3 of the tie. They

are formed by providing reenforcing ribs 7 on the underside of the tie top, as indicated in dotted lines in Figures 1 and 3. These ribs 7 then are pressed toward the top wall of the tie so that instead of these lower ribs 7 upper transverse ribs 2 are produced.

However the wall of each rib 11, remote from the rail foot has a cavity or recess 13 adapted to lodge the T-shaped head of the respective width of the rail foot. These ribs 11 extend the entire width of the top 3 of the tie. They

are formed by providing reenforcing ribs 7 on the underside of the tie top, as indicated in dotted lines in Figures 1 and 3. These ribs 7 then are pressed toward the top wall of the tie so that instead of these lower ribs 7 upper transverse ribs 2 are produced.

However the wall of each rib 11, remote from the rail foot has a cavity or recess 13 adapted to lodge the T-shaped head of the respective width of the rail foot. These ribs 11 extend the entire width of the top 3 of the tie. They

are formed by providing reenforcing ribs 7 on the underside of the tie top, as indicated in dotted lines in Figures 1 and 3. These ribs 7 then are pressed toward the top wall of the tie so that instead of these lower ribs 7 upper transverse ribs 2 are produced.

ribs 11 on both sides of the cavity 13, each pair of ribs 17 forming stops for an adjusting clip (not shown) and preventing motion of the clip in the direction of the track. The bearing surfaces 18, Figure 6, for the outer leg of the clip may lie at the same level as the top surface of the tie or may lie at a somewhat lower level, as indicated by a dotted line in Figure 6, left side, whereby the introduction of the fixing bolt is facilitated or its head may be made somewhat higher. If required, strengthening ribs 19 may be provided on the underside of the top wall 10 of the tie 9 which ribs may be produced in the course of rolling the tie. The transverse ribs 11, strengthening ribs 17 as well as the cavity 13 and recess 16 may be produced by one and the same pressing operation whereby the manufacture of the tie is notably simplified and rendered less expensive.

In the embodiment of the improved tie illustrated in Figures 7 to 9, the transverse ribs 20 are produced by pressing them out of the top material of the tie 32. Each of these ribs 20 has full inner and outer vertical side walls 22 and 23, respectively, without any recess, while in the top wall existing between these two vertical side walls there is provided an oblong or rectangular hole 25, Figure 8, which may be punched out at the same time that the ribs 20 are pressed. In this embodiment the space existing between the walls 22 and 23 is only so large as to receive the rectangular head of the fixing bolt 26. The bearing faces of the head 27 of bolt 26 abut on the underside of the top wall of the tie, the bolt 26 being protected from turning by a square portion 28 provided on its shank. As may be seen in Figures 8 and 9, the ribs 20 subside into the top surface of the tie 32 by sloping surfaces 29 which extend from their walls 22, and form recesses 30 on the surface of the tie. These recesses receive the outer legs of the clips 31. In applying the bolt 26, its head 27 is introduced in the oblong hole 25 and the bolt lowered to such an extent that after turning it 90° the head 27 engages the underside of the wall 24 of the tie.

The top wall 24 of the tie may be rolled throughout with a suitable uniform thickness, or may be thickened only at the bearing places. The dimensions of the dies used for making the ribs 20 and oblong holes 25 may be chosen in such a manner that the material forced away in the pressing operation serves to strengthen the adjacent walls so that the oblong holes are flanged. In this way, as well as by suitably rounding the edges of the holes, any formation of cracks and the like is overcome.

What we claim and desire to secure by Letters Patent is:—

1. A railway cross tie having transverse ribs at the top thereof adapted to guide the foot of a rail on both sides, said ribs being

integral with the tie and extending continuously across the entire width thereof, each of said ribs furthermore defining a chamber comprising a lateral continuous wall facing the foot of the rail, said chamber adapted to receive a rail fixing member. 70

2. A railway cross tie having transverse ribs at the top thereof adapted to guide the foot of a rail on both sides, said ribs being integral with the tie and extending continuously across the entire width thereof, each of said ribs furthermore defining a chamber comprising a lateral continuous wall facing the foot of the rail and an opening upon the underside of said rib, said chamber adapted to receive a rail fixing member. 75

3. A railway cross tie having transverse ribs at the top thereof adapted to guide the foot of a rail on both sides, said ribs being integral with the tie and extending continuously across the entire width thereof, each of said ribs furthermore defining a chamber comprising a lateral continuous wall facing the foot of the rail, said chamber adapted to receive a rail fixing member, the bearing surface of the tie between two companion ribs being convex in the longitudinal direction of the track. 85

4. A cross tie as specified in claim 1, in which said transverse ribs are pressed out of the top wall of the tie. 90

5. A cross tie as specified in claim 1, in which the top wall of the tie is reenforced on the underside, said reenforced portions serving to replace the material pressed out of the top wall to form said transverse ribs. 100

6. A railway cross tie having transverse ribs at the top thereof adapted to guide the foot of a rail on both sides, said ribs consisting of integral portions of said tie pressed from the top thereof and defining cavities open at the underside adapted to receive the head of a fixing bolt, and recesses in said ribs opening outwardly of said rail adapted to receive the shank of the fixing bolt. 105

7. A cross tie as specified in claim 6, in which corner ribs are provided between said transverse ribs and the top surfaces of the tie on the side remote from the rail. 110

8. A cross tie as specified in claim 6, in which reenforcing ribs are provided on the underside of the tie extending in the longitudinal direction thereof. 115

9. A cross tie as specified in claim 6 wherein corner ribs are provided between said transverse ribs and the top surface of the tie on the side remote from the rail, said latter portion of the top surface being depressed to a lower level than the remainder of said top surface and adapted to receive the outer legs of rail clips. 120

10. A railway cross tie having transverse ribs at the top thereof adapted to guide the foot of a rail on both sides, said ribs consisting of integral portions of said tie pressed 125

from the top thereof and defining cavities open at the underside adapted to receive the head of a fixing bolt, and apertures at the top of said ribs in which the head of a rail fixing bolt is adapted to be inserted.

11. A railway cross tie having transverse ribs at the top thereof adapted to guide the foot of a rail on both sides, said ribs consisting of integral portions of said tie pressed from the top thereof and defining cavities open at the underside adapted to receive the head of a fixing bolt, and rectangular apertures at the top of said ribs adapted to pass the rectangular head of a fixing bolt and cooperate with said head in its turned condition as a lock for said bolt.

12. A railway cross tie having transverse ribs at the top thereof adapted to guide the foot of a rail on both sides, said ribs consisting of integral portions of said tie pressed from the top thereof and defining cavities open at the underside adapted to receive the head of a fixing bolt, each of said ribs having a lateral continuous wall facing the foot of the rail and an aperture at the top adapted to receive a rail fixing member, said ribs furthermore subsiding by sloping surfaces from said lateral walls outwardly of the rail into the top surface of the tie.

30 The foregoing specification signed at Berlin, Germany, this 21st day of October, 1931.

VALENTIN HERWIG.
ERNST MUSTIN.
